METHOD OF APPLYING BACKING FABRICS TO LININGS

Application filed October 21, 1930. Serial No. 490,318.

This invention relates to a method of and means for applying backing fabrics to silk linings, and it has reference particularly to a novel method of attaching backing fabrics, such as fleeced cotton, to silk linings of that character used in the interior decoration of caskets and the like.

Explanatory to the present invention, it will here be stated that caskets, coffins, and the like, are, as a general rule, lined and decorated with silk, which is crushed, crinkled or formed in puffs of various shapes or characteristic designs, and these designs are held in shape by sewing the silk which forms them to a backing piece. This backing serves additionally as a supporting means for attaching the decorative lining to the walls of the casket. It is a very painstaking, tedious and expensive operation to sew the backing fabrics to the crushed silk lining. In fact, this work is generally done by hand and is one of the most expensive items in the manufacture of caskets, since it is required that each fold, or puff of the crushed silk be attached by a fine thread or stitch so applied as not to be noticeable.

Heretofore, many attempts have been made to devise a method whereby the crushed silk could be attached to the backing by use of an adhesive, but prior to the present invention, these attempts have been unsuccessful, or at least very unsatisfactory for the reason that it was impossible to apply the glue or adhesive in such manner that it would not show through the thin silk or cause stiffness to the fabric. There was the difficulty of spreading the glue and, if it was applied to the backing in sufficient quantity to hold the silk, it would penetrate through and spot the surface. It is essential when an adhesive is used, that it be so distributed and so thinly applied that it will not be absorbed by the silk but will dry without penetration, and it is also essential that it shall not cause stiffness, or give any impression of stiffness to the finished article.

In view of the many difficulties that heretofore have been experienced in the attempts made to attach backing pieces to silk by use of glue, or other adhesive, and in view

of the expensiveness of the usual sewing process, it has been the principal object of this invention to provide a successfully, inexpensive, and very desirable method whereby an adhesive may be applied in such fine quantities and so evenly spread that it will not be absorbed by the silk, or show through its surface when the backing is applied thereto, and which will serve more effectively to hold the lining than is possible by sewing.

Other objects of the invention reside in the various order of steps followed out in practising the process.

The practising of the present method contemplates the use of certain mechanism, the preferred forms of which have been illustrated in the accompanying drawing, wherein—

Fig. 1 is a perspective view, showing a preferred form of equipment used in carrying out the process.

Fig. 2 is a cross sectional view of the parts.

Fig. 3 is an enlarged sectional detail, illustrating the attachment of the backing to the silk piece.

While the present process relates especially to the applying of backing fabric to silk linings of caskets, it is to be understood that it is not to be limited thereto, but is just as applicable to other uses where silk, or the like, is attached to backing. The process, briefly stated, consists of first applying a thin film of gum to a glass plate, or other foundation, then pressing the fleeced or nap side of a backing fabric against the gummed surface, thence removing the backing and applying the nap side to the crushed silk so that the gum which adheres to the nap will cause the backing to adhere to the silk.

In carrying out the present process, I employ a gum, or adhesive, that is especially prepared to adhere to silks and thin fabrics without striking through, yet to have sufficient strength for all purposes for which it is used in the casket making industry. The gum, which I employ is used to best advantage with a backing material having a nap such as that of fleeced cotton, sometimes called "domet", and it is best especially for the casket industry, to use a long fleeced cot-

ton so that the fleece will serve as connecting threads between the silk and backing piece, as will presently be explained.

The particular design or form in which 5 the silk is crushed, and the type of crushing machine used for forming it into the various designs is immaterial to the present invention. Any standard crushing machine 10 on the market today will do. However, a machine of the type illustrated in United States Patent Nos. 1,733,353, and 1,724,493, issued on October 29, 1929, and August 13, 1929, respectively, may be employed for crushing the silk into various designs. 15 These machines, as will be observed from their descriptions, operate to form a silk lining piece into puffs of various characteristic designs. The backing fabric is then attached to this, then the work is removed 20 from the machine for application to the casket wall.

To carry out the process to the best advantage, I provide along side of this crushing machine, which is designated in its entirety 25 by reference numeral 1, a glass plate, or other foundation, of sufficient size to take care of a backing piece for any lining that may be formed in the machine. The glass plate 2 is supported vertically between up- 30 rights 3 and 4 and upper and lower cross pieces 5 and 6. This installation is close to the machine 1 for convenience, and of such height that all parts of the glass can be easily or conveniently reached. Across the 35 bottom of the frame is a shelf 7 on which the gum, or adhesive containers 8 may be placed for ready access thereto. It is desirable that the frame be so located that the workmen may pass clear around it. Across 40 the top bar 5 and along the opposite side bars of the frame, at the side opposite the machine, are brads 9, or other supports on which a backing fabric 10 may be suspended and stretched across the back side of the 45 glass plate; it being supported in this way in order that the operator may see exactly the place and size of the area of glass to which the gum is to be applied, and, if any particular design is to be followed, this may 50 first be marked in pencil on the fabric piece and when it is suspended back of the glass, the marks may be seen through the glass and followed in applying the gum. After the silk has been crushed in the desired design, 55 the gum is applied to the glass plate, either by means of an air gun or spray, or by use of the usual hand brush. When the hand brush is used, the gum is placed on the glass by dipping the brush into the container of gum and then spotting the glass 60 with the gum at close intervals, then by spreading it lengthwise of the plate, then up and down, and then again lengthwise to insure an even spreading and thickness. This 65 should be evenly and very thinly applied.

Experience will soon teach how thick the adhesive should be initially applied, and the pull on the brush will enable one to tell when it is of proper tackiness.

Immediately after the adhesive has been spread over the glass, and when it has reached the proper tackiness, the fleeced fabric piece is removed from the back side of the glass plate and is applied to the adhesive side so that the fleece thereof engages with the gum. It is then smoothed out with a paper hanger's brush, or with the hands, and then, without delay, the backing is pulled off the glass and laid upon the crushed silk so that the fleece engages the silk. There should be a slight pulling necessary to remove the fabric from the glass. If there is no pulling, this will indicate that there is too much gum applied, and in such event, it is best to wait a few minutes longer to permit the gum to become tacky. After the fabric has been placed upon the silk, it is then smoothed down with a soft brush or whiskbroom, after a few moments setting, the work is finished.

In this process of transferring the gum from the glass plate to the fabric, there is the advantage that the gum may be evenly spread to a very exact thickness which cannot be done if the gum is applied directly to the fabric. Also, the gum may be spread so thin on the glass that there is not enough to penetrate, either the backing or silk, and therefore, it does not spot, or show through the silk of the thinnest quality.

A feature of this process which makes it a success, is that the individual threads of fleece are pulled out on end and each carries a very minute quantity of gum at its end which acts as a connecting body between that particular thread and the silk piece. This has been illustrated in Figure 3, wherein 15 designates the fleece and 16 the particles of gum at their ends.

Another feature resides in the fact that the gum or adhesive is so sparingly used that it does not stiffen the backing or silk. All gum is held away from the warp or weave of the fabric and the nap, being drawn out on end forms a very noticeable cushioning medium between the silk and fabric which, in fact 115 lends softness to the finished product.

The advantages of the above transfer method of applying the gum are that the gum holds the silk better than when hand sewed. There are no stitches to show through the silk, and no punctures are made by the use of needles; neither is it necessary to steam the crushed silk to help keep the design in place; it holds the design better than three stitches with thread will do, and the use of gum saves approximately three-fourths of the time that is usually required where the fabric is applied by stitching with thread.

Having thus described my invention, what 130

I claim as new therein and desired to secure by Letters Patent, is:

1. The method of attaching backing fabric to crinkled lining materials, consisting of applying an adhesive to a superficiary, then spreading the backing fabric upon the superficiary while the adhesive is tacky, then removing the backing from the superficiary and while it is drawn smooth applying the side thereof, made tacky by transfer of adhesive from the superficiary, to the lining material. and whereby the area of the plate to which adhesive is applied is in registration with the marked area on the backing, then pulling the backing from the plate to cause the fleece to be drawn out on end, then spreading the backing upon the lining and brushing them together to cause them to be attached by reason of adhesive transferred from the plate to the fleece. 70
- Signed at Seattle, Washington this 14th 75 day of October 1930.
- ALBERT R. MAULSBY.
2. The method of attaching backing fabric to crinkled linings, consisting of thinly spreading an adhesive over a smooth surface, then spreading the backing fabric upon said surface while the adhesive is tacky, then pulling it away from said surface to effect the transfer of adhesive to the backing, then while it is drawn smooth spreading the tacky side of the backing upon the lining and brushing them together to effect their attachment by reason of the adhesive transferred to the backing. 80
3. The method of attaching fleeced fabric to linings, consisting of thinly spreading an adhesive upon a smooth surface, then spreading the backing fabric upon said surface with its fleeced side against the tacky adhesive, then pulling it from said surface to effect the transfer of the adhesive to the fleece, then applying the backing upon the lining to cause the fleeced side thereof to adhere to the lining by reason of the adhesive transferred thereto. 85
4. The method of attaching fleeced fabric to crushed silk linings consisting of thinly applying an adhesive material to a glass plate, applying the fleeced side of the backing fabric to the glass plate while the adhesive is tacky, then pulling it from the plate, and spreading it upon the lining and brushing them together whereby they are caused to adhere by reason of the adhesive transferred to the fleece. 100
5. The method of attaching fleeced fabric to silk linings consisting of thinly spreading an adhesive upon a glass plate, applying the fleeced side of the backing to the plate, then pulling it off to draw the fleece out on end and effecting the transfer of adhesive to the fleece ends, then spreading the backing upon the lining to cause it to adhere thereto by reason of the transferred adhesive at the fleece ends. 105
6. The method of attaching fleeced fabric to silk linings, consisting of first preparing the lining, then marking the outline of the lining on the backing, then suspending the backing against one side of a glass plate so that the marked outline may be seen through said glass plate, then thinly spreading an adhesive upon the other side of the glass plate within the area marked on the backing, then applying the backing piece to said plate with its fleeced side in contact with the adhesive 110
